PORTABLE BATTERY-OPERATED TOOL

Marnie C. Averitt, Timonium, James E. Dickson, Towson, and Marshall B. Johnson, Fallston, Md., assignors to The Black and Decker Manufacturing Company, Towson, Md., a corporation of Maryland

Filed Nov. 10, 1965, Ser. No. 88,059

Term of patent 14 years

(Cl. D54—14)

FIG. 1

FIG. 3

FIG. 2

FIG. 4

FIG. 5

FIGURE 1 is a top plan view of the portable battery-operated tool embodying our design;

FIGURE 2 is a side elevation;

FIGURE 3 is a front elevation;

FIGURE 4 is a rear elevation; and

FIGURE 5 is a bottom view.

The dominant features of my design reside in the portions shown in full lines.

We claim:

The ornamental design for a portable battery-operated tool, as shown and described.
